FRUIT BASKET

William S. Luckett, New York, N. Y.

Application October 13, 1933, Serial No. 693,517

3 Claims. (Cl. 217—124)

The purpose of this invention is to provide a basket made of paper or paper products, resembling a grape basket, having a handle adapted to take the load from a superimposed basket or baskets and transmit said load to the bottom of the basket thereby protecting the contents thereof, and in which the handle is so formed that it may readily be inserted by hand instead of requiring a machine as is now used.

10 The invention is an open carton made of paper or paper products or wood having a wire handle held in the sides thereof and extending to the base so that a load from an object positioned above the basket will be transmitted directly to 15 the base.

Baskets of this type which are normally used as grape baskets have formerly been made of thin wood slats and these have been shipped without the handles being in place and it has required a special machine to install the handles in the upper edges of the sides of the basket. Other carriers of this type have been provided having wood handles, however, it is difficult to pack these devices for shipping and it is practically impossible to improve their appearance without using a special lining or wrapping.

The object of this invention is, therefore, to provide a carrier or basket of the type used for 30 grapes or the like which may be made of paper or paper products and in which the handle supports the sides and rests upon the base so that loads on the handle will be transmitted directly to the base.

35 Another object is to provide a grape basket in which the machines used for installing the handles are eliminated.

A further object is to provide a basket which may be used for grapes, fruits, or the like, which 40 may readily be printed or decorated or provided in various color designs.

And a still further object is to provide a grape basket in which the manufacturing cost is substantially reduced.

45 With these ends in view the invention embodies a basket having tapering sides made of paper or paper products or wood having a wire handle which may be held in openings and notches in the sides, and also having a cover that may be held in different positions by indentations provided in the handle.

Other features and advantages of the invention will appear from the following description taken 50 in connection with the drawing, wherein:

55 Figure 1 is a cross section thru the basket

showing the design and arrangement of the handle.

Figure 2 is a side elevation of the basket.

Figure 3 is a view showing a method of packing the baskets with one above another and with 5 each resting upon the handle of the basket below.

Figure 4 is a plan view of the cover.

Figure 5 is a plan of a cover of an alternate design.

In the drawing the basket is shown as it would 10 be made wherein numeral 1 indicates the basket, numeral 2 the handle, and numeral 3 the cover.

The basket 1 is preferably made of paper, cardboard, or paper products, however, it will be understood that it may be made of wood, or of 15 any material, or of any composition of materials. The sides and ends may also be made plain, as shown, or may be shaped in any manner, or may be made similar to the wooden grape baskets now in use. In this design the lower 20 edges of the sides, which are indicated by the numerals 4 and 5, are provided with openings 6 into which the lower ends 7 and 8 of the handle 2 may be inserted, as shown in Figures 1 and 2, and the upper edges of the sides are provided 25 with notches 9 into which extensions 10, projecting inward from the sides of the handle 2, may be placed, as shown. The sides, ends, and bottom of the basket may, otherwise, be plain or may be made of any shape and in any design. 30 The basket may also be made of a rectangular shape, as shown, with two long and two short sides, or it may be made of any other shape and the sides and ends may be made in any proportion 35 in relation to each other.

The handle 2 is preferably made of comparatively heavy wire, however, this may be made of any material and the cross section of the material may be of any shape. In the design shown it is made with a comparatively straight central portion 11, from the ends of which the material is bent downward and inward to form projections 12, and from these projections the material is bent outward to the points 13 and then inward to form the extensions 10 thereby providing recesses 14 above the upper edges of the basket and from the lower sides of the extensions 10 the material extends downward forming straight sections 15 and at the lower ends of these sections the material is bent inward to form the ends 7 50 and 8 which rest upon the base 16 of the basket. It will be noted that with the handle formed in this manner the lower ends may readily be spread so that they may be inserted in the openings 6 and as soon as they are released, they will 55

spring back into the position shown in Figure 1 in which the extensions 10 extend into the notches 9 and the sections 15 support the sides 4 and 5 at the center of the basket. It will be understood, however, that the sides or legs of the handle may be of any other shape or design, may be arranged in any other manner, may be held in the basket by any other means, and any other means may be provided for holding them in the upright position. It will be noted that in Figure 1 of the drawing the sections 15 and the lower end of the handle are spaced from the walls and base of the basket in order to illustrate the construction, whereas the sections 15 actually contact the surfaces of the side walls and the ends 7 and 8 rest upon the base.

The baskets may be provided with a thin cover board 3, as shown in Figures 4 and 5, and this may be provided, as shown in Figure 5, or with curved ends, as shown in Figure 4, and either design may be provided with notches 17 which will seat upon the projections 12 of the handle in order to locate and hold the cover above the basket.

When the baskets are first packed, the cover 3 may be placed in the upper part of the handle, as indicated by the dotted lines 18, and in this position it will rest upon the projections 12 and thereby protect the fruit or other products therein. As the products settle, the cover may be removed and placed in the recesses 14 so that it will rest upon the upper edge of the basket, as shown in Figure 1, and it will be understood that means may be provided in the handle for holding the cover in any other position or positions.

It will be understood that other changes may be made in the basket without departing from the spirit of the invention. One of which changes may be in the use of any number of handles with one basket or container, another may be in the use of other means for inserting the handles in the basket, another may be in the use of handles with shorter ends as it will be understood that it is only necessary to extend the ends 7 and 8 thru the sides 4 and 5, and still another may be in the use of other means for holding the cover to the basket.

The construction will be readily understood from the foregoing description. In use a plurality of baskets may be packed and shipped nested, that is, with one basket inside of another and the handles may be shipped independent. Before packing the baskets, or after the baskets are packed, the handles may be inserted by spreading the ends 7 and 8 and placing them in the openings 6, as hereinbefore described, and then the covers 3 may be inserted in the handles. The filled baskets may then be packed in a carton with one above the other, as shown in Figure 3, so that the handles will hold the upper basket and prevent any pressure whatever being placed upon

the contents thereof. The sides of the baskets will engage the inner walls of the carton in which the baskets may be packed which will hold them in the upright position and the handles will keep them spaced apart.

It will be noted that by forming the handles in this manner, the handles may readily be inserted by hand so that it is not necessary to use a machine to form or crimp the handles in place and as the lower ends of the handles extend downward to the base of the basket, all load and strain is removed from the side walls and transmitted directly to the base. These handles also extend over the side walls and support the same thereby preventing bulging with the fruit or other products therein. The handle, therefore, supports the basket in all directions, and takes all upward and downward pressures or loads. This handle may also be used with the wooden baskets now in use or with baskets, carriers, or containers of any other type or description.

Having thus fully described the invention, what I claim as new and desire to secure by Letters Patent, is:

1. A basket made of cardboard having sloping sides adapted to be nested with similar baskets having notches centrally positioned in the upper edges of the side walls and means in the lower edges of the side walls positioned below said notches for holding the lower ends of handles, a handle in which the lower ends are adapted to be inserted in the holding means of said side walls by hand and projections adapted to be inserted into the notches of said side walls and other projections adapted to hold a cover, the lower ends of the handle extending across the base of the basket and resting thereon and a cover adapted to be suspended upon the projections of said handle and also adapted to rest upon the upper edges of the side walls of said basket.

2. A basket as described in claim 1 in which notches are provided in the sides of the cover for locating the cover on the handle.

3. In combination, a carton of the type open at the upper end, a detached removable cover adapted to rest upon the upper edges of the sides, and a handle formed substantially in a rectangle open in the center of the lower side and adapted to be sprung open to insert the ends of the lower side in openings in the side walls of the carton positioned just above the base in order that the parts of the said lower side may rest upon the base, the vertical sides of said handle having loops extending inward into openings in the upper edges of the sides of said carton, and additional loops also extending inward positioned above the edges of the sides of the carton upon which the cover may rest to hold the cover above the carton.
